US00D878557S

(12) **United States Design Patent** (10) **Patent No.:** **US D878,557 S**
(45) **Date of Patent:** **** Mar. 17, 2020**

(54) **INJECTOR DEVICE**

(71) Applicant: **West Pharmaceutical Services, Inc.**, Exton, PA (US)
(72) Inventors: **Jason Williams Farris**, Gilbert, AZ (US); **Samuel Dauphinais**, Phoenix, AZ (US); **Brian Costello**, Whitehouse Station, NJ (US); **Raymond Protasiewicz**, Whippany, NJ (US)

(73) Assignee: **West Pharmaceutical Services, Inc.**, Exton, PA (US)

(**) Term: **15 Years**

(21) Appl. No.: **29/619,381**

(22) Filed: **Sep. 28, 2017**

Related U.S. Application Data

(63) Continuation-in-part of application No. 29/582,288, filed on Oct. 26, 2016, now Pat. No. Des. 806,234.

(57) **CLAIM**

The design of an injector device, as shown and described.

DESCRIPTION

FIG. 1 is a top, front, right perspective view of an injector device of our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an exploded perspective view thereof.

The dashed line portion of the drawings is included to show unclaimed subject matter only for the purpose of illustrating environment and forms no part of the claimed design.

The broken lines show portions of the design that form no part of the claimed design.

1 Claim, 8 Drawing Sheets
